UNITED STATES PATENT OFFICE.

CLIFFORD A. CUTLER, OF BUFFALO, NEW YORK.

DRYING-KILN.

1,341,884.

Specification of Letters Patent.

Patented June 1, 1920.

Application filed August 26, 1918. Serial No. 251,407.

To all whom it may concern:

Be it known that I, CLIFFORD A. CUTLER, a citizen of the United States of America, and a resident of Buffalo, county of Erie, 5 and State of New York, have invented a new and useful Drying-Kiln, of which the following is a specification.

It is well known to those skilled in the art, that in order to properly dry lumber it 10 is necessary that there should be a rapid circulation of air through the kiln and the lumber contained therein, so that the air will be quickly passed through the lumber before it has a chance to lose its heat.

15 The principal object of my invention has been, therefore, to provide a kiln in which there shall be a strong and rapid circulation of air. This circulation of air is made substantially uniform throughout the kiln 20 by providing a plurality of small fans.

Another object has been to provide a kiln in which the incoming cold air shall automatically balance the outgoing warm air, and one in which, therefore, the cold air 25 shall not enter in such a manner as to cause a difference in temperature in the lumber.

Another object has been to provide a kiln having means for the separation and withdrawal from the kiln of the foul, moisture- 30 laden air contained therein.

Moreover, my kiln is so constructed that the heated air passing through the lumber gives off some of its heat to the incoming cold air as it is drawn downwardly through 35 the kiln; and, this, together with the provision of a plurality of small fans, makes it possible to operate my kiln in a very inexpensive, effective, and economical manner.

The above objects and advantages have 40 been accomplished by the device shown in the accompanying drawings, of which:

Figure 1 is a fragmentary, sectional, plan view of my kiln, taken on line 1—1 of Fig. 2.

Fig. 2 is a fragmentary, longitudinal, sectional elevation of the kiln, taken on line 45 2—2 of Fig. 1.

Fig. 3 is a transverse, sectional view of my kiln, taken on line 3—3 of Fig. 2.

Fig. 4 is an enlarged, fragmentary, sectional view of the air-control valve, taken 50 on line 4—4 of Fig. 2.

Fig. 5 is an enlarged, fragmentary, sectional view, of one of the air inlet valves, and is taken on line 5—5 of Fig. 2.

55 My kiln comprises, preferably, two side walls 10 and a rear wall 11, each preferably

of brick or concrete construction. The front wall of the kiln is formed by a curtain 9, suitable means (not shown) being provided for raising and lowering the curtain. 12 is 60 the roof of the kiln which is supported, in the usual manner, by a plurality of rafters 13. A ceiling 14 is arranged below the rafters, and strips 15 are provided between the ceiling and the rafters, thus providing spaces 65 16 therebetween.

Arranged through the roof 12 of the kiln is a plurality of air intakes 17. These intakes are preferably constructed with a gable 18 arranged over the open, upper ends, 70 so that air may have free access thereto. The lower end of each of these intakes extends into one of the spaces between the rafters and each is provided with an air-inlet valve 19 (see Fig. 5). This valve is secured upon 75 a pivotally mounted shaft 20, having a sprocket 21 attached thereto. A sprocket chain 22 passes over the sprocket 21 and has its ends secured to an operating wire 23. This wire is controlled manually by any 80 suitable, well-known means, which does not form a part of this invention, and, therefore, is not shown. Each of these intakes 17 supplies air between the adjacent rafters, and the space 16 provides for the communication 85 of all of the spaces between the rafters, so that the air may readily circulate over the top of the ceiling 14. At each side of the ceiling and running longitudinally of the kiln is a longitudinal slot 24. An air-control 90 valve 25 (see Fig. 4) is arranged over each of these openings and is carried by a pivotally mounted shaft 26. The shaft 26 is suitably supported and provided at one end with a sprocket 27. A sprocket chain 28 passes 95 over the sprocket and has operating wires 29 attached to its ends. These operating wires extend across the kiln and connect with the ends of the sprocket chain at the other side thereof. The air-control valves 100 with their sprockets and sprocket chains are identical and, for clearness in the drawings, only one is shown. The wires 29 are preferably crossed, so that the sprockets will be operated in reverse directions, there- 105 by opening and closing the valves 25 in unison. The valve operating shaft at one side of the kiln is provided with an additional sprocket which is connected with suitable, manually operated means, whereby the air-control valves may be manually controlled.

110 As the operating sprocket wheel and manu-

ally operated means do not form a part of this invention, they are not shown.

30 is the floor of the kiln, which slopes downwardly toward the side walls 10, except for a portion near the center of the kiln, where it is level. At each side of the floor, adjacent the outer walls, there is provided a trough 31, which is comparatively narrow at the front end of the kiln and 10 tapers gradually to the rear end thereof where it is quite wide. The trough 31 meets and joins a trough 32 which extends transversely of the kiln, adjacent its rear wall 11. 33 is an exhaust duct which is arranged adjacent the rear wall 11, and has its lower end located some distance above and over the trough 32. A ventilator 34 is preferably provided at the upper end of the duct for increasing the draft of air through the same.

A plurality of I-beams 35 are provided for the support of the lumber, and they are arranged at each side of the kiln, thus leaving a clear space through the center thereof. 25 Each of these I-beams is supported at its outer end by the side wall 10 and at its inner end by a post or abutment 36. These I-beams are arranged some distance above the floor 30 of the kiln so as to provide for the 30 free circulation of air along the floor. The lumber when placed upon the supports 35 is preferably stacked as shown by the sectional view of Fig. 3. As here shown, the lumber is stacked with a V-shaped opening 37, tapering from the bottom of the pile upwardly, and with a space 38, adjacent each side wall, which is closed at the top by lumber on the top of the pile.

Beneath the I-beams 35 is arranged a plurality of small electric fans 39, which provide the circulation of air in my kiln. These fans, as shown in Fig. 1 are arranged so as to direct the air from the front side of the kiln to the rear thereof and are inclined somewhat inwardly so as to draw the air from the center aisle and force it toward the side walls. Any desired number of these fans may be provided and their arrangement may be varied to suit conditions.

50 My kiln is provided with suitable heating means preferably in the form of steam coils. A steam coil 40 is arranged within each of the spaces 38 and a steam coil 41 is arranged beneath each row of I-beams 35. These coils 55 are, of course, connected with a suitable source of steam supply and are controlled manually in any well-known manner. A steam pipe 42, having perforations, extends lengthwise into the kiln, whereby additional 60 moisture may be supplied to the lumber, if required.

After the lumber has been stacked in the kiln, as shown and described, and the steam turned on at the steam heating coils, the 65 fans 39 are started. The air inlet valves 19

and the air-control valves 25 being partially open, the fans 39 will draw air through the intakes 17, through the longitudinal slots 24 in the top 14 of the kiln, and down through the center aisle provided between the stacks of lumber. It will be caught by the fans when it reaches this point and be forced backwardly and toward the side walls, over the steam coils and up the openings 37 and the spaces 38 with great velocity. The lumber is, of course, stacked so that there is a space between adjacent pieces and the air current will be forced in through between the lumber.

As the heated air is forced through the lumber, it takes up a good deal of the moisture in the lumber. If the air is not very moist it will be recirculated through the kiln by means of the fans; but if the air is foul and heavily moisture-laden, it will drop to the floor of the kiln and move downwardly along the inclined surface thereof, till the troughs 31 are reached. The general circulation of the air will carry this moisture-laden air along the troughs and 90 into the end trough 32, whence it will be taken up the duct 33 and exhausted into the atmosphere. The air currents just above described are shown by the arrows in Fig. 3; and it will be seen that the heated 95 air coming from the lumber will meet the incoming cold air and interchange some of its heat with this cold air. It is obvious that the valves 19 and 25 will be regulated so as to supply the proper quantities of fresh air 100 to the kiln to replace the moisture-laden air exhausted therefrom.

If desired, the number and location of fans and steam coils may be varied at will to meet the conditions required by the 105 different kinds of lumber. These and other modifications of the details herein shown and described may be made without departing from the spirit of my invention or the scope of the appended claims; and I do not, 110 therefore, wish to be limited to the exact embodiments herein shown and described.

Having thus described my invention, what I claim is:

1. The combination, with a kiln having 115 walls and a ceiling, of a plurality of supports arranged above the floor, air intakes in the ceiling, means for providing a plurality of air blasts arranged in the space between the floor and the supports, and an air 120 exhaust duct, opening near the bottom of the kiln.

2. The combination with a kiln having walls, a ceiling and a false ceiling, of a plurality of supports arranged above the floor, 125 air intakes in the ceiling, the false ceiling being formed with air openings, means for regulating the openings in the false ceiling, means for providing a plurality of air blasts arranged in the space between the 130

floor and the supports, and an air exhaust duct opening near the bottom of the kiln.

3. The combination with a kiln having walls and a ceiling, of a plurality of supports arranged above the floor, the supports being so arranged as to provide a clear central space in the kiln for the free passage of air therethrough, air intakes in the ceiling, means for providing a plurality of air blasts arranged in the space between the floor and the supports, and an exhaust duct opening near the bottom of the kiln.

4. A kiln comprising side walls, a ceiling, a plurality of supports arranged above the floor, two stacks of lumber carried by the supports, the lumber being so piled as to provide a clear central space in the kiln and a clear space adjacent each side wall for the free circulation of air therethrough, means for providing a plurality of air blasts arranged in the space between the floor and the supports, and an air exhaust duct opening near the bottom of the kiln.

5. The combination, with a kiln having walls and a ceiling, of a plurality of supports arranged above the floor, air intakes in the ceiling, means for providing a plurality of air blasts arranged in the space between the floor and the supports, an air exhaust duct opening near the bottom of the kiln, and heating means arranged near the bottom of the kiln.

6. The combination, with a kiln having walls and a ceiling, of a plurality of supports arranged above the floor, air intakes in the ceiling, means for providing a plurality of air blasts arranged in the space between the floor and the supports, an air exhaust duct opening near the bottom of the kiln, and heating means arranged near the side walls of the kiln.

7. A kiln comprising side walls, a ceiling, a plurality of supports arranged above

the floor, two stacks of lumber carried by the supports, the lumber being so piled as to provide a clear central space in the kiln and a clear space adjacent each side wall for the free circulation of air therethrough, means for providing a plurality of air blasts arranged in the space between the floor and the supports, an air exhaust duct opening near the bottom of the kiln, and heating means arranged adjacent the lumber.

8. The combination, with a kiln having walls and a ceiling, of a plurality of supports arranged above the floor, air intakes in the ceiling, means for providing a plurality of air blasts arranged in the space between the floor and the supports, a longitudinal trough formed in the floor of the kiln and arranged adjacent each of the side walls, and an air exhaust duct opening near the bottom of the kiln.

9. The combination, with a kiln having walls and a ceiling, of a plurality of supports arranged above the floor, air intakes in the ceiling, means for providing a plurality of air blasts arranged in the space between the floor and the supports, a transverse trough adjacent the rear wall of the kiln, and an air exhaust duct located above and over the transverse trough.

10. The combination, with a kiln having walls and a ceiling, of a plurality of supports arranged above the floor, air intakes in the ceiling, means for providing a plurality of air blasts arranged in the space between the floor and the supports, a longitudinal trough provided in the floor of the kiln and arranged adjacent each of the side walls, a transverse trough adjacent the rear wall of the kiln connecting the longitudinal trough, and an exhaust duct located above and over the transverse trough.

In testimony whereof, I have hereunto signed my name.

CLIFFORD A. CUTLER.
